ELECTRICAL COIL STRUCTURE FOR
TRANSFORMERS

Charles A. Schwartz, Elyria, Ohio

Application April 10, 1948, Serial No. 20,283

8 Claims. (Cl. 175—356)

1

This invention relates to the coil structure of electrical power devices and apparatus and more particularly to the arrangement and structure of the coils in electrical transformer units.

In any device or apparatus containing electrically conducting media, the passage of the electrical current therethrough, in some degree, results in heat energy which is dissipated. In power applications, where the electrical energies involved are substantial, the generation of heat which is inherent in electrical devices, greatly influences the design and size of the devices and the rapid dissipation of the heat becomes an important factor in preventing the attainment of critically high temperatures which would impair or destroy these devices.

In apparatus such as alternators and induction coils, but more particularly in heavy duty transformers, forced cooling of the apparatus must be employed, and the size of the electrical conductors employed in such apparatus is to a large extent determined by the efficiency of the cooling system is dissipating the heat which is evolved.

For example, it is common practice in the construction of transformers for welding machines to employ water cooling coils for the secondary coil of the transformer. The heat which is generated by the primary coil must pass through the electrical insulation on the individual conductors and then must pass through the electrical insulating barrier between the primary and secondary coils before it is able to be absorbed by the cooling medium. As the electrical insulators are inherently also good thermal insulators, the heat generated by the primary coil is dissipated much less rapidly than that of the secondary coil and the primary will attain much higher temperatures than the secondary coil.

It is a primary object of my invention to provide a coil structure which encourages the rapid passage of heat from the electrical coils to the cooling medium.

Another object of my invention is to provide a transformer construction in which the primary coil is formed in a matrix of either thermally or thermally and electrically conductive material.

Still another object of my invention is to provide a transformer construction in which the coils form a substantially rigid unitary mass whereby vibration of the conductors is inhibited.

A further object of my invention is to provide a transformer structure which will permit a reduction in the physical size of a transformer as compared to the size of transformers currently used for equivalent output rating.

2

A still further object of my invention is to provide an electrical coil construction which due to its efficiency in heat dissipation permits the use of smaller conductors than presently used at stated amperage ratings.

Other objects and advantages of my invention will become apparent during the course of the following description.

Although, for purposes of illustrating an embodiment of my invention, I refer generally throughout the description to welding transformers, I wish to emphasize that my invention is applicable to and equally effective in a broad class of coil wound electrical apparatus, including but not limited to alternators, electro-magnets, induction heating coils and rotary transformers.

In the accompanying drawings, forming a part of this specification and in which like numerals designate like parts throughout the same.

Fig. 1 is a longitudinal cross-sectional view taken on line 1—1 of Fig. 2, of a transformer embodying my invention, portions thereof being broken away to show certain details of the invention.

Fig. 2 is a cross-sectional view, taken on line 2—2 of Fig. 1.

Fig. 3 is a fragmentary cross-sectional view, taken on line 3—3 of Fig. 1.

Fig. 4 is a fragmentary cross-sectional view, taken on line 4—4 of Fig. 1, showing the insulating barrier across the secondary coil of my transformer.

Fig. 5 is a plan view of a modified form of my invention, portions thereof being broken away to show certain details.

Fig. 6 is a cross-sectional view, taken on line 6—6 of Fig. 5, showing the modified coil structure.

Fig. 7 is a view in elevation showing the application of my transformer to a welding machine.

Referring more particularly to Figs. 1 to 4 of the drawings, the numeral 1 designates generally a welding machine transformer which embodies the features of my invention. In the form shown, the transformer comprises a shell 2 formed of electrically conductive material such as copper, a primary coil 3, a secondary coil 4 and a laminated iron core 5.

The primary coil 3, which in this instance is 50 the high voltage winding, is formed of conductor wire 6 which is coated with a high temperature insulating material 7 such as woven glass fiber impregnated with silicone varnish or, preferably, a material of the ceramic type. The primary coil 55 3 is formed by winding the individual turns of

the conductor wire 6 on a specially formed bobbin, so as to form a space-wound coil, relatively large and uniform spaces being left between the respective turns and layers of the coil.

The space-wound primary coil 3 is adapted to be placed and contained within the shell 2. The shell is generally rectangular in shape, and has a channel-like cross-section consisting of a bottom 8, an exterior wall 9 and an interior wall 10. For convenience, the four interior walls are designated as 10a, 10b, 10c and 10d, and the exterior walls are designated as 9a, 9b, and 9c. No exterior wall is provided along the side of the shell opposite the interior wall 10d, as to this portion of the shell are firmly affixed, as by brazing, solid copper blocks 11 and 12, which as will hereinafter more fully appear, serve as the electrical terminals of the secondary coil 4.

It will be noted that the blocks 11 and 12 are separated from each other by a narrow gap 13, which is filled with insulating material 7, and that the electrical continuity of the shell 2 is likewise interrupted by a transverse gap 14 in the interior wall 10d and the bottom 8 of the shell, the gap 14 being in effect a continuation of the gap 13.

The blocks 11 and 12 are provided with recesses 15 and 16 respectively, these recesses serving to accommodate portions of a copper tube 17 which is formed to serve as a cooling coil 18 when liquid coolant, such as water, is passed therethrough. The wall 9a of the shell 2 is provided with an opening 19 through which the inlet end 20 and the outlet end 21 of the cooling coil 18 may project.

The primary coil 3 and the cooling coil 18 are of such size and form that the primary coil 3 can be placed between the upper and lower turns of the cooling coil, the copper tubing 17 thereby lying in close proximity to the end turns of the primary coil. The primary coil 3 and cooling coil 18, assembled as aforesaid, are placed within the shell 2, the ends 22 of the coil 3 being disposed in proximity to circular openings 24 provided in the exterior wall 9a of the shell.

It is well to state at this point, that the spacers (not shown) which were originally utilized in winding the coil 3 may all be removed with the exception of one which is designated by the numeral 25. Dabs of ceramic slurry or the like at spaced points within the coil will, when set, serve to maintain the turns in spaced relationship after the spacers are removed. The spacer 25 is so disposed as to be in registry with the gap 14 in the shell 2 when the assembly of the coil 3 and cooling coil 18 are placed within the shell 2 as aforesaid. The spacer 25 is completely covered with the insulating medium 7 so as to form an insulating barrier 26 which extends completely across the portion of the shell 2 which is defined by the gap 14. The layers of conductor wire 6, of course, extend through the barrier 26 due to the manner in which the primary coil 3 was originally formed.

I will now describe my method of forming the secondary coil, which in this instance is the low voltage coil. The secondary coil 4 may be formed in general of any low-melting metallic alloy such as those of lead, silver or tin of the group commonly referred to as "solders." Those alloys which have relatively better characteristics of electrical conductivity being, of course, preferred. I have found that I am able to improve the electrical and thermal conductivity of some of these solders by mixing therewith granular or powdered copper particles.

The secondary 4 is formed by pouring the molten metal into the shell 2, completely filling the shell and the spaces between the turns of the coil 3. A copper cover plate 23, which conforms to the shape of the shell 2, is placed over the shell to further increase the strength and conductivity of the secondary 4. The molten metal bonds the copper cover plate to the shell 2 and to the secondary coil 4. When the metal has cooled and solidified, it forms a solid matrix for the primary coil 3, completely enveloping the turns of the coil 3 and firmly supporting the conductor wire 6 and the copper cooling coil 18.

Although I have found the casting method of forming the secondary coil 4 to be the most practicable, it is also possible to utilize other methods for forming the matrix, such as, for example, metal spraying, electroplating, and sintering (powdered metals).

Prior to the casting of the secondary coil 4, I secure the ends 22 of the primary coil 3 to terminal posts 27, which are secured to the wall 9a of the shell by means of the insulator bushings 28 and retainers 29, the posts 27, of course, being insulated from the shell 2 and the secondary coil 4.

Power line cables (not shown) are connected to the terminal posts 27 and it will be apparent that the primary circuit of the transformer is thus established through the coil 3.

It will also be apparent that the solid matrix, the continuity of which is broken by the barrier 26, forms the secondary circuit or coil 4 consisting of a single turn, the terminals of which are the blocks 11 and 12. In the illustrated form, I have shown welding electrodes 30 affixed to adapters 31 in the blocks 11 and 12.

The transformer construction above described has considerable advantage over the transformer structure which is currently employed in the art. The intimate relationship of the primary and secondary coils results in greater efficiency of transformer operation due to very low leakage reactance. Heat generated in the primary coil 3 passes rapidly through the thin insulating coating 7 and is conducted through the solid matrix to the cooling coil 18 which is imbedded therein. I have found that heat dissipation can be effected so rapidly in a transformer embodying my invention, that I can readily employ conductor wire 6 having a cross-sectional area equivalent to 25 circular mils per ampere and still maintain the operating temperature of the transformer well below the point where it would become injurious to the transformer. By comparison, it is to be noted that it is conventional practice in transformer construction to employ conductors having areas in the range of 300 to 1000 circular mils per ampere.

The fact that I am thus able to efficiently utilize from one-fortieth to one-twelfth the mass of conductor wire employed for the primary coil in transformers of conventional construction, in turn, results in a substantial reduction in the overall size of a transformer embodying my invention as compared to one of conventional design. The decreased size of my transformer, apart from its obvious economical advantage, permits its use directly on a resistance welding machine, the electrodes 30 being mechanically secured directly to the terminal blocks 11 and 12 of the transformer. This integration of the transformer with the welding machine, has heretofore, due to space limitations, been possible only in very special applications. It will be obvious that, if, for example, a series of spot welds

two inches apart is desired, the pairs of welding electrodes can be integrated with the transformer terminals only when the physical space occupied by the transformers will permit them to be aligned side by side on four inch centers. Welding transformers, as presently constructed, are required to be so large as generally to prohibit the integration of the transformers with the welding machine. Therefore, it is in most cases necessary to place the transformer at some distance from the welding machine, and to electrically connect the welding electrodes to the low voltage terminals of the transformer by means of conductor cables.

The connector cables themselves use large quantities of copper and add to the cost of welding installations. However, this initial expense is greatly overshadowed by still another factor of cost. This second factor is the cost of the excess electrical energy which must be purchased to overcome the energy losses which occur as the weld current flows through the cable connectors. To handle this additional flow of electricity, the transformer, in turn, has to have a higher rating, and is, therefore, larger than is actually necessary to supply the desired weld current through the electrode tips.

The reduced size of a transformer embodying my invention, permits, in most applications, the mounting of the transformer directly on the welding machine, integrally with the welding electrodes, and is of great importance in that it eliminates the use of cable connectors between the welding electrodes and the terminals of the secondary coil. The energy losses, which occur when the weld current flows through the cable connectors are likewise eliminated and the transformer terminal voltage may thereby be reduced to less than one-half of that which is required when cable connectors are necessary. Thus a transformer of lower output rating can be employed to produce welding currents which are in all respects equivalent to those obtained with the use of a cable connected transformer of higher load rating and larger size.

The lower output voltage required not only reduces the overall cost of the electrical power supply charges, but also permits the physical size of the transformer to be decreased still more.

Referring now to Figs. 5 and 6 of the drawings, I have shown a modified form of welding transformer 1' which embodies the same principle upon which the previously described structure was based.

The modified form represents two major departures from the structure shown in Figs. 1 to 4. Firstly, the secondary coil and terminal blocks are a unitary casting formed of relatively high-melting alloys having good characteristics of mechanical strength. Secondly, the spacing between the layers and turns of the primary coil is modified so as to dispose a series of insulating barriers across the layers of the coil, as will more fully hereinafter appear.

Ordinarily, in welding applications, the energy losses in the transformer—the so-called iron and copper losses—are but such a small percentage of the total losses which occur in the welding circuit, that they merit little attention. Therefore, the structure shown in Figs. 1 to 4 would not be objectionable for most welding applications, even though the eddy current loss in the primary coil would be fairly high. However, in certain special welding applications and in many other transformer applications, such high eddy

current loss may be objectionable and undesirable.

In order to reduce this eddy current loss, I fabricate the primary coil 3' in the manner shown in Fig. 6. The coil is wound on a specially formed bobbin, as aforementioned, however the spaces *s* between the layers of the winding are made greater than the spaces *t* between the turns of the coil. A large medial space *m* is also provided between the turns of the coil 3', for a purpose to be hereinafter described.

After the primary coil 3' has been wound, it is dipped in a semi-viscous slurry of ceramic insulation 7. Due to the cohesiveness of the slurry and the small space *t* between the turns of the conductor wire 6, the insulation forms a series of insulating barriers 32 which extend across each layer of the coil 3. The conductor wires 6 will therefore not be completely surrounded by the metallic matrix, as they were in the embodiment shown in Fig. 2. The insulating barriers serve to limit and restrict the eddy current paths and therefore serve to reduce the eddy current loss which, as previously stated, may in some cases be objectionable.

The ends 22 of the primary coil are secured to the terminal posts 27, which, in turn, are partially enveloped in ceramic insulation 7, so as to insulate the posts from the secondary coil. An insulating barrier 26 is also provided on the coil 3', as in the previously described embodiment.

The primary coil assembly is placed in a mold which is provided with suitable cores, and the secondary coil 4' is formed by pouring molten metal such as copper or aluminum alloys into the mold. Due to the high thermal and electrical conductivity of the metal used, and its relatively good characteristics of mechanical strength, it is unnecessary to utilize the copper shell 2 in this modified structure.

Through the use of cores, a circuitous conduit or channel 33 is formed in the cast metal in the space *m* and serves as a coolant path having its inlet as at 34 and its outlet as at 35. The terminal blocks 11' and 12' are formed integrally with the secondary coil 4' and may be sawed or otherwise machined or cast so as to form the gap 13 which is filled with insulation 7.

The blocks 11' and 12', as well as blocks 11 and 12 shown in Fig. 1, may be strengthened by tie-bolts 36 which are insulated from the blocks by insulating sleeves 37 and washers 38. The bolts 36 extend through openings 39 formed in the blocks and are secured by nuts 40.

The terminal posts 27 are supported by the solid secondary coil 4', thus eliminating the requirement for the bushings 28 and 29, previously referred to. The transformer structure is completed by mounting thereon the laminated iron core 5.

In Fig. 7, I have illustrated one of the ways in which my transformer structure could be utilized for a spot welding application. The electrodes 30 are mounted directly on the terminal blocks 11' and 12' of the secondary coil 4' of the transformer. The transformer, in turn, is resiliently secured as by insulated bracket 41 to a piston 42 of a pneumatic cylinder assembly 43. An insulated flexible joint 44 is interposed between the ends of the piston 42 and the blocks 11' and 12', which, in combination with the resilient bracket mounting 41, permits equalization of the pressure brought to bear on the blocks by the piston, thereby permitting proper registry of the electrodes with the work to be welded.

It is to be noted that the integration of the electrodes 30 with the transformer is made possible by the small physical size of a transformer constructed in accordance with this disclosure, and that I thereby eliminate the cable connectors and obtain the several advantages heretofore enumerated.

It is to be understood that various features of each of the embodiments which I have shown are to a great extent applicable to both the transformers 1 and 1'. For example, the primary coil 3 may be embodied in transformer 1' and the primary coil 3' may be embodied in the transformer 1; or, the copper cooling coil 18 may be embodied in the transformer 1' instead of forming the cored out channel 33.

It is also to be understood that, in accordance with the common practice in the art, both the primary and secondary coils, or either of them, may be "tapped" or supplied with leads at a plurality of positions in order to permit selective variation in the electrical performance of the transformer. Additional variations may also be utilized, for example, the coolant coil 18 may be secured exteriorly of the coil structure under circumstances where it may be expedient, and further, the cooling circuit through the secondary coil can be connected to and made continuous with a cooling circuit through the welding electrodes, such as is commonly employed in the art.

The improved structure which I have disclosed, and which for purposes of illustration I have shown as a transformer, may with equal advantage be employed in other types of coil-wound electrical apparatus, to which I have previously referred. For example, any large electro-magnet, such as used in a cyclotron, can effectively employ my improved coil structure to obtain more efficient cooling of the coils. The structure is equally applicable to the coils of large alternators particularly to the armature windings, in which case the matrix serves only as a heat conductor and does not have to have good characteristics of electrical conductivity. By short circuiting the secondary coil, the highly efficient cooling structure may also be utilized in induction heating coils to permit the heating of large items at power frequencies. Numerous other applications of my improved coil structure will be apparent to those skilled in the art, without necessity for their detailed enumeration herein.

In addition to the advantages of my improved structure, which I have previously enumerated, I wish to point out that the rigidity of the coil structure is such that substantially all of the audible vibration customarily associated with transformer operation is eliminated and the coil structure is itself more rugged and less susceptible to injury.

It is to be understood that the forms of my invention, herein shown and described, represent specific examples of the same and that various changes in the shape, size and arrangement of parts may be resorted to, without departing from the spirit of my invention or the scope of the subjoined claims.

Having thus described my invention, I claim:

1. An electrical coil structure for transformers and the like, said structure comprising a primary coil of insulated conductor wire consisting of a plurality of layers of turns with the layers in spaced relation to each other, and a solid metallic matrix of good electrical conductivity in which said primary coil is embedded, the electrical con-

tinuity of said matrix being interrupted transversely of said primary coil to form the terminals of a single turn secondary coil of the structure, the layers of said primary coil being separated from each other by said matrix and each layer being enveloped thereby, whereby to quickly dissipate the heat generated in said primary coil.

2. An electrical coil structure for transformers and the like, said structure comprising a primary coil of insulated conductor wire consisting of a plurality of layers of turns, with the layers in spaced relation to each other, and a solid metallic matrix of good electrical conductivity in which said primary coil is embedded, said matrix being interrupted transversely of said primary coil to form the terminals of a single turn secondary coil of the structure, the layers of said primary coil being separated from each other by said matrix, with the matrix surrounding a substantially large portion of each turn of the primary coil, whereby heat generated in said turns is readily dissipated in said matrix, and a conduit extending through said matrix for passage of a cooling medium for removing heat from the matrix.

3. An electrical coil structure as defined in claim 2 wherein each turn of said primary coil is completely enveloped by said matrix.

4. An electrical coil structure as defined in claim 2 in which barriers of insulating material are provided between adjacent turns in each of said layers, whereby to restrict the eddy current paths in said solid matrix.

5. An electrical coil structure, as defined in claim 2 including an iron core disposed about said coil structure.

6. An electrical coil structure, as defined in claim 2, in which the secondary coil is of generally U-shaped form, the arms and bight portion of said secondary coil encompassing three sides of said primary coil, the terminals of said secondary coil being disposed in proximity to the fourth side of said primary coil, and solid metallic blocks are secured to the terminals of said secondary coil.

7. An electrical coil structure for transformers and the like, said structure comprising a space wound primary coil of insulated conductor wire consisting of a multiplicity of layers of turns, with the layers in spaced relation to each other, a single turn secondary coil of generally U-shaped form consisting of a solid metallic matrix of good electrical conductivity which envelopes said layers and fills the spaces between said layers and lies in intimate heat conducting relationship to the turns of said primary coil, the arms and bight portion of said secondary coil encompassing three sides of said primary coil, said secondary coil having terminals arranged adjacent each other at the fourth side of said primary coil, and a cooling conduit extending through said matrix for passage of a heat removing medium.

8. An electrical coil structure, as defined in claim 7, in which said matrix also fills the spaces between the turns of wire in each layer of said primary coil.
